UNITED STATES PATENT OFFICE

126,702

DESIGN FOR A DISPLAY CASE

Wallace St. Clair Jones, Cambridge, Mass.

Application September 28, 1940, Serial No. 95,504

Term of patent 7 years

To all whom it may concern:

Be it known that I, Wallace St. Clair Jones, a citizen of the United States, residing at Cambridge, county of Middlesex, Commonwealth of Massachusetts, have invented a new, original, and ornamental Design for a Display Case, of which the following is a specification, reference being had to the accompanying drawing, forming part thereof.

The figure is a perspective view of a display case, showing my new design.

I claim:

The ornamental design for a display case, as shown,

WALLACE ST. CLAIR JONES,
